PANEL ARRANGEMENT FOR DISPENSING PUMPS

H. Hix Wolfe, Dayton, Ohio, assignor to The Dayton Pump and Manufacturing Company, Dayton, Ohio, a corporation of Ohio

Application February 7, 1949, Serial No. 74,961

4 Claims. (Cl. 312—100)

1

This invention relates to pumps, and particularly to improvements in the construction of dispensing pumps for fuels and similar fluids, such as gasoline, kerosene, naphtha, and the like.

Pumps of the nature referred to above are principally used in filling stations, and comprise a pumping and metering device and a computer and indicator connected with the meter for indicating the amount of liquid dispensed and the total cost. The pumps are housed in a panelled enclosure, and it is desirable that the panels be so arranged that only authorized persons can remove them so that there will be no tampering with the operating parts of the pump. This is a protection for the filling station operator as well as the purchaser.

Since pumps of this type are used in many different places, it is desirable to provide for some ready means of modifying the appearance thereof so they can be adapted for use under different circumstances.

It is one object of this invention to provide for an improved construction for the framing and housing of a dispensing pump of the type referred to above which has a better appearance than pumps constructed according to the prior art, and in which certain of the enclosing panels can easily be removed from the pump so that the mechanism on the inside can readily be serviced or replaced.

It is a still further object of this invention to provide a construction for a dispensing pump or the like having one or more panels which are locked in position by a key operated device and which serve positively to retain the other panels and covering members for the pump structure in position.

It is also an object of this invention to provide an arrangement for a dispensing pump having a totalizing counter so arranged that only authorized persons can view the said counter and thus determine the amount of fluid dispensed by the pump over any given period.

A still further object of this invention is the provision of an adapter for the dome member of dispensing pumps of the type referred to, such that the pump can conveniently be adapted for use with an illuminated top globe if desired, or can be used without the said globe.

A general object of this invention is to provide a construction for dispensing pumps and the like which is easier to construct than pumps of the prior art, and in which all of the panels forming the enclosure of the pump are so formed as to be rigid so as to resist deformation.

2

and so interlocked when mounted on the framing of the pump structure that they cannot be removed except by operation of a key operated lock.

These and other advantages will become more apparent upon reference to the following description taken in connection with the accompanying drawings in which:

Figure 1 is a perspective view showing a dispensing pump constructed according to my invention;

Figure 2 is a perspective view of the framing of the pump and showing the base, the corner angles extending upwardly from the base, the top plate connecting the corner angles and the shelves mounted between the corner angles and which support the various operating auxiliaries of the pump;

Figure 3 is a view looking in at one indicating face of the pump as indicated by the arrow marked 3 in Figure 1 but with the covering panel for that side of the pump removed;

Figure 4 is a view looking in from the right side of Figure 3 and with the front and rear panels of the pump in cross-section;

Figure 5 is a plan section indicated by the line 5—5 on Figure 3 and showing the arrangement of the front and side panels of the pump and the interlock therebetween;

Figure 6 is a plan section indicated by the line 6—6 on Figure 4 and showing the latching and locking mechanism by which the front and rear panels which cover the indicating faces of the pump are retained in position on the pump frame;

Figure 7 is a fragmentary sectional view indicated by the line 7—7 on Figure 4 and showing one of the snap-in fasteners for releasably retaining the front and rear panels in position;

Figure 8 is a view indicated by the line 8—8 on Figure 4 and showing the arrangement for operating the totalizer mask by one of the latch mechanisms of the front and rear panels;

Figure 9 is a section indicated by the line 9—9 on Figure 4 and showing an adapter member mounted in the dome of the pump housing; and

Figure 10 is a view similar to Figure 9 but showing how the adapter in the dome of the pump can be inverted so as to act as a base and holder for a globe which is illuminated by a light bulb therein.

Referring to the drawings somewhat more in detail, a pump constructed according to my invention generally comprises a base member 10

having side panels mounted therein, as indicated at 12, and also having front and rear panels, as indicated at 14. These last mentioned panels are apertured as at 16 so that the indicating faces 18 of the pump can be viewed. The outer enclosing structure of the pump is completed by a covering dome member 20. These several parts will be best seen in the perspective view Figure 1.

The interior of the pump, comprising the frame work which supports the panels referred to above, and which also supports the operating auxiliaries of the pump, such as the pump proper, its drive motor, the meter, and the computer and indicator mechanism, is illustrated in Figure 2. In Figure 2 it will be noted that there is upstanding from the base 10 a plurality of angle members 22. These angle members are positioned at the corners of the base and are secured thereto by means of the posts 24 upstanding from the said corners of the base 10. Bolts 26 pass through these posts and the webs of the angles 22. This post arrangement and the manner in which it is secured to the corner angles will also be seen in Figures 2, 3, 4, and 5.

The upper ends of the corner angles are connected by a top plate 28 which not only rigidly joins the said angles, but also serves as a supporting means for certain of the pump auxiliaries and as a support for the dome member 20. The bolts 30 may be provided for interconnecting the top plate 28 and the corner angles, as shown.

A plurality of shelves, as at 32, 34 and 36, are provided for supporting the pump, meter, and computer and indicator for the pump. These shelves extend between the straps or brackets 38 that are connected between adjacent of the corner angles as by means of the bolts 40. The construction of the shelves and the supporting brackets therefor will be better seen in my co-pending application, Serial No. 3,628, filed January 21, 1948, and assigned to the same assignee as the instant application.

Other elements and parts of the pump frame construction of this invention which are to be seen in Figure 2, will be referred to hereinafter and reference numerals applied thereto.

Referring now to Figure 5, it will be noted that the side panels 12 have marginal flanges extending along the side edges thereof, as indicated at 42, and which secure the said panels to the corner angles 22 as by means of the bolts 44, as will be seen in Figures 3, 4, and 5. The lowermost edge of each of the side panels 12 is preferably turned inwardly, as indicated at 46, and this serves not only to stiffen the panels, but also to provide a good bearing surface thereof against the base 10 of the pump and to improve their appearance.

The upper ends of the side panels 12, as will best be seen in Figure 3, are formed inwardly and then upwardly, as indicated at 48, so as to telescope with the dome member 20 of the pump housing. This telescoping of the side panels with the dome member not only gives a positive interlock between the said panels and dome member, but also provides for a weather seal, preventing moisture and foreign matter from readily entering the inside of the pump housing.

The front and rear panels of the pump, namely, those indicated at 14 and comprising the windows 16 through which the indicator faces 18 of the pump are visible, are formed so that their side portions enclose the marginal flanges 42 of the side panels 12, as indicated at 50, in Figure

5. It will be noted in Figure 5, and also in Figure 4, that the marginal portions of the front and rear panels 14 are rolled completely around, and this assists in stiffening the panels and giving them a better appearance.

The front and rear panels each carry on their bottom parts a pair of pilot pins 52, best seen in Figure 4, and which are adapted for entering the bores 54 in the base member 10. This aligns and positively locates the panels 14 when they are placed in position on the pump frame.

Adjacent their upper ends, each of the front and rear panels 14 carries at each side a necked-in stud best illustrated at 55 in Figure 7. When the panels 14 are mounted in position the studs 55 extend through the apertures 56 in the marginal flanges of the side panels 14 and the brackets 58 bolted to the corner channels 22 and engage the spring clips 60 mounted on the backs of the brackets 58. When the pilot pins 52 are in their bores 54 and the necked-in studs 55 are snapped in their retaining clips, the front and rear panels of the pump are supported in the position in which they appear in Figures 1 and 4.

Turning now to the operating auxiliaries of the pump, the lowermost shelf arrangement 36 is adapted for supporting the pump and motor for the dispensing pump of this invention and which are indicated, respectively, at 60 and 62 in Figures 3 and 4. The pump is connected by the conduit 64 with the underground tank or reservoir from which the dispensing pump draws the fluid to be dispensed, and discharges through the conduit 66 to the meter 68 which is mounted on the shelf 34. The fluid which passes through the meter is conveyed by the conduit 70 through the sight flow arrangement 72 mounted in the top of the pump casing and then passes through the conduit arrangement 74 to the hose 76 and dispensing nozzle 78.

The meter 68 includes a rotary part which is connected by the shaft 80 with the computer and indicator generally indicated at 82 and supported on the uppermost of the shelves 38. The aforementioned sight flow arrangement includes a pair of transparent members 84, one at each side of the pump, and these members extend through apertures in the panels 14. This will best be seen in Figures 1 and 4. The dome member 20, as will best be seen in Figures 3 and 4, is formed to extend over the members 84 and includes the outwardly extending and turned up flanges 86 which telescope with the turned in edges 88 of the panels 14. As in the case of the panels 12, the dome member 20 is thus positively interlocked with the panels 14 and also provides a weather and dirt seal to prevent moisture and foreign matter from entering the inside of the pump housing.

It will be noted in connection with Figure 3 that the dome member 20 is adapted for being retained in position by the clips 90 secured inside the covers thereof and including straps which extend inwardly to overlie bosses 92 integral with the top plate 28. Bolts 94 clamp the straps to these bosses and thus retain the dome member 20 in position.

As mentioned before, the front and rear panels 14 are adapted for being locked in position by a key operated mechanism. This portion of the pump is best illustrated in Figures 3, 4, 6, and 8. In these views it will be noted that each of the panels 14 has secured to the inside face of its

turned-in edge part a channel member 96 which opens toward the outer face of the panel. This channel, it will be noted, is adapted, when the associated panel 14 is mounted in position on the pump, to enter the cut-out notches 98 provided for that purpose in the adjacent webs of the angles 22 and the marginal flanges of the side panels 12. Each of the angles 22 carries a retaining clip 100 which has an end part adapted to extend through the aperture 102 provided therefor in the aforementioned channel 96 when the channel is placed in the notch 98.

The channel 96 reciprocably supports a pair of plungers 104, the ends of which are adapted for engagement with the turned over ends of the clips 100. The plungers 104 are slidably supported at their outer ends by the apertured brackets 106 and are pivotally connected at their inner ends to the bar 108 which is fastened to the locking mechanism 110 so as to be rotated by a key placed therein. It will be apparent that rotation of the locking mechanism 110 will either engage the plungers 104 with the clips 100 or disengage the plungers from the said clips. The panels 14 can thus be removed from the pump frame only when the proper key for the lock 110 is available. Since the panels 14 are interlocked with the panels 12 and the dome part 20, it follows that none of the panels or the dome can be removed except when the proper key is available.

The indicator face visible from the right side of the pump as it is drawn in Figure 4 is illustrated in Figure 8 and on this side there is a totalizing counter, the dials of which are indicated at 112. According to this invention there is provided a masking member 114, which in one position will conceal the indicating dials 112, and in another position will expose the said dials for observation. This masking member is pivoted at 116 behind the face of the indicator, and a chain 118 is connected for moving the masking member between its two positions. The end of the chain 118 is connected to one arm of the bell crank lever 120 which is also pivoted behind the indicator face of the pump and which includes another arm extending downwardly as at 122 and through an opening 124 in the adjacent channel 96. The arm 122 through the opening 124 lies close beside one of the plungers 104, and on this plunger there is a collar 126 adapted for abutting the side of the said arm. Upon reference to Figure 8, it will be noted that when the plungers 104 are withdrawn to their unlocked position, the masking member is moved to position to expose the indicating dials 112. However, when the plungers 104 are moved outwardly into their panel locking position, the said masking member is dropped into the position indicated by the dot-dash outline in Figure 8, and thus conceals the indicating dials from observation. It is, therefore, necessary to operate the lock 110 in order to be able to observe the indicating dials 112. This insures that only authorized individuals having keys for the pump will be able to observe the totalizing indicators.

As mentioned before, this invention also proposes the provision of an adapter member mounted in the dome part 20 of the pump housing and which can be utilized as a base for supporting a globe on the said dome member if desired. This feature is best illustrated in Figures 9 and 10 where it will be observed that the dome member 20 is centrally apertured as at 130 by a shouldered opening and which opening is adapted for receiving a closure member 132. This closure

member is retained in position by the screws 134 which engage the plate 136 overlying the lower marginal edge of the periphery of the aperture 130 in the dome member. The closure member 132 is centrally apertured as at 138 and in Figure 9 this aperture is closed by a removable part 140.

The arrangement shown in Figure 9 is utilized when it is not desired to mount a globe on the top of the pump and it will be noted that the member 132 provides for a smooth and uninterrupted exterior for the dome member 20.

When it is desired to support a globe on the top of the pump, the member 132 is inverted as indicated in Figure 10. When the member 132 is so placed, it is retained in position by the same screws 134 which engaged the same retaining plate 136 and presents an upwardly opening channel part 142 adapted for receiving the base of a globe 144. The outer flange surrounding the channel 142 is adapted for receiving a plurality of screws 146 which overlie the lower end of the base of the globe 144 and thereby retain it positively in position.

The aforementioned central aperture 138 of the member 132 is utilized for supporting a socket base 148 into which the light bulb 150 can be placed. The lead-in wires for supplying electric current to the light bulb 150 to illuminate the globe are brought out through the aperture 138 as indicated at 152 in Figure 10. It will be apparent that the adapter member 132 thus fulfills a dual function and that the globe 144 can either be mounted on the pump or the pump can be utilized without the globe merely by a simple inversion of the said member 132.

The particular features of the improved dispensing pump arrangement above described and which I desire to secure by Letters Patent, include the improved panel arrangement, the formation, support and interlocking thereof; the locking means for the removable panels having the windows therein for viewing the indicator faces; the masking device for the totalizing counters and the interlock thereof with the locking mechanism for one of the releasable panels; and the reversible adapter member mounted in the upper dome part of the pump housing. These several features are all more particularly set forth in the appended claims, and it will be understood that I desire to comprehend within my invention such modifications in construction and proportions, and such substitution of equivalents, as may be considered to come within the spirit of the invention and the scope of the appended claims.

I claim:

1. In a dispensing pump having a plurality of interfitting panels and a supporting frame therefor, one of said panels having rolled back margins, a channel extending transversely across the said one of said panels and connected at its ends to said margins, plungers slidably carried in said channel, a key operated device for moving said plungers between inner and outer positions, and means on said frame to engage the ends of said plungers in their outer position for thereby retaining said panels in position, said channel being provided with apertures adjacent its ends for receiving the said means.

2. In a dispensing pump having a plurality of interfitting panels and a supporting frame therefor, one pair of said panels having rolled-back margins, channels extending transversely of said panels and secured to the insides of said rolled-back margins, locking means including plungers

carried by said channels between the channels and the insides of the said pair of panels, means on the frame for engagement with the ends of the plungers, and said channels being provided with apertures for admitting said means when said panels are placed against said frame. 5

3. A panel for a dispensing pump comprising a sheet of metal generally concave on its pump side and having a rolled in margin on its concave side, a member extending transversely of the panel and secured to the panel side of the rolled in margin, and locking mechanism including reciprocable locking plungers carried by said member on its panel side, said member being apertured adjacent its ends to receive clips adapted for engagement with said locking plunger. 10

4. A panel for a dispensing pump comprising a sheet of metal generally concave on its pump side and having a rolled in margin on its concave side, a member extending transversely of the panel and secured to the panel side of the rolled-in margin, and locking mechanism including reciprocable locking plungers carried by said member on its panel side, there being a key operated part on said mechanism extending 20 through the front of the panel so as to be accessible from outside the pump for operating said plungers, said member being apertured adjacent its ends to receive clips adapted for engagement with said locking plunger. 25

sible from outside the pump for operating said plungers, said member being apertured adjacent its ends to receive clips adapted for engagement with said locking plunger.
